UNITED STATES PATENT OFFICE.

CHARLES W. BALDWIN, OF COUNCIL GROVE, KANSAS.

TRAP-DOOR.

SPECIFICATION forming part of Letters Patent No. 794,968, dated July 18, 1905.

Application filed February 17, 1905. Serial No. 246,003.

To all whom it may concern:

Be it known that I, CHARLES W. BALDWIN, a citizen of the United States, residing at Council Grove, in the county of Morris and 5 State of Kansas, have invented certain new and useful Improvements in Trap-Doors, of which the following is a specification.

This invention relates to means for locking, releasing, opening, and holding in open position cellar or trap doors of the style that is 10 built or let into a floor.

The especial objects of my improvements are to provide means having the functions named that can be cheaply manufactured and 15 applied, that will be easy to operate, which will be safe and effective in use, and in which the danger of the person using being struck by any of the operating parts will be reduced to a minimum.

20 In the accompanying drawings, which form a part of this application, Figure 1 is a view in side elevation showing my invention applied to a trap-door, the latter being shown in an open position. Fig. 2 is a top plan view 25 of the parts shown in Fig. 1. Fig. 3 is an elevation of the door open and looking from the inside, parts being broken away to more clearly show the construction; and Fig. 4 is a detail of the door-latch and its attachments, 30 which form a part of my invention.

Referring to the drawings in detail, I have shown a section of floor built of boards A on longitudinal timbers a^4 a^5 and cross-pieces a' a'' and with a suitable doorway cut in same, 35 to which a trap-door B is applied. Hinges b^6 secure one end of the door to the flooring, so that it may open in the usual manner. At the free end of the door and to its under side is secured a catch b^3 of well-known form. 40 Near the hinged end of the door and on the under side is secured a projecting bracket b^5 , through which a hole is formed to permit the passage of a lever C. This lever is a piece of round iron bar or pipe, is bent at c' and 45 at one end to form a hook c^2 , and has an iron ball c^3 mounted on it and held in place by a set-screw c^4 . The hooked end of the lever is secured to the under side of the door near the free end of the latter. It is desirable to 50 have the lever attached at a point equidistant

from the sides of the door and at the same time to so arrange it that a person passing through the doorway will not be likely to come in contact with the lever or its counterweight c^3 ; hence the connections shown 55 and the bend c' . In general practice trap-doors are placed near a foundation or partition-wall, and it is my intention to so arrange the lever C that the weighted portion will come next to such wall, and hence be out of 60 the way.

To engage the catch b^3 , I pivot on the cross-piece a' a latch D, having a hook on its free end. To one side of the latch a contraction spring d^1 is secured, the other end of which 65 is connected with the timber a^4 . To the opposite side of the latch a link d^2 connects a bell-crank d^3 , which is pivoted at d^4 to the cross-piece a' . A rod d^5 is connected with the other arm of said crank and passes upwardly 70 through a suitable opening out in the floor and has its free end bent over, as indicated in Fig. 2.

Constructed as above described and with the weight c^3 properly adjusted on the rod C 75 to overbalance the weight of the door the latter may be opened by pushing down on the rod d^5 , thus releasing the catch b^3 from the latch D, and thereby permitting the door to open on its hinges. It will be apparent that 80 the releasing-rod d^5 may be placed at a considerable distance from the catch D, and it can therefore be located close to the wall or at some other point where it could not be accidentally operated.

85 In order to hold the door open, a bar b^4 is loosely secured near one edge of the hinged end of the door and provided with a weight on its free end so offset that it will cause the bar to swing outwardly so as to catch on the 90 floor adjacent to the doorway. To release the door, it is only necessary to kick the bar inwardly.

Having thus described my invention, what I claim as new, and desire to secure by Letters 95 Patent, is—

1. The combination with a hinged door provided with a catch, of a lever secured at one end and midway its ends, to said door and provided with an adjustable counterweight, a 100

latch pivotally mounted in position to engage said door-catch and held under yielding tension, a bell-crank connected with said latch, and a rod connected with said crank, and 5 passing upwardly through the floor to which said door is hinged, whereby depressing said rod, will release said catch.

2. The combination with a hinged door provided with a catch, of a weighted lever bent 10 substantially as described and secured at one end to the under side of the door midway its side edges, said lever also secured midway its ends to the under side of said door near the hinged end of the latter, of a latch pivotally 15 mounted in position to engage said catch and

held under a yielding tension, a pivoted bell-crank connected with and adapted to operate said latch, a rod connected with and adapted to operate said crank, said rod passing inwardly through the floor, and a bar secured to said door near its hinged end and adapted to hold the door in an open position independently of said lever. 20

In testimony whereof I affix my signature in presence of two witnesses.

CHARLES W. BALDWIN.
